ALIPHATIC-AROMATIC AMINE AND PROC-
ESS OF MAKING SAMEKarl Wilhelm Rosenmund and Fritz Küls, Kiel,
GermanyNo Drawing. Application February 8, 1933, Serial
No. 655,762. In Germany April 27, 1931

9 Claims. (Cl. 260—127)

Our invention relates to the production of new chemical compounds designed for use in the therapeutic treatment of certain ailments, and more especially to tertiary amines of the aliphatic-aromatic series, which may be substituted for papaverine in all the uses to which this well known remedy is put.

As is well known to those skilled in the art, papaverine is dispensed nowadays in an ever increasing degree but its use is hampered by certain unpleasant secondary effects, which render it desirable to replace the papaverine by other compounds having the same beneficiary effect, but lacking these unpleasant properties.

We have now found that in order to obtain the beneficiary effect of papaverine it is not necessary that an isoquinoline nucleus be present, and that compounds which contain the typical phenyl radicals of the papaverine without having undergone condensation into an isoquinoline nucleus, are superior in some respects to the papaverine.

great number of compounds belonging to this class, amongst others the following:

1. Bisphenylethyl-ethylamine

2. Bis-phenylethyl-allylamine

3. Phenethyl-phenisopropyl-methylamine

4. (Alpha, beta-diphenyl)ethyl-phenylethyl-propylamine

5. O-methoxy-phenethyl-phenethyl-ethylamine

6. Bis-(3,4-dimethoxy-phenethyl)methylamine

7. Beta-methoxy-beta-phenethyl-phenethyl-methylamine

8. Gamma-phenylpropyl-benzyl-methylamine

9. Bis(gamma-phenylpropyl)-ethylamine

10. Delta-phenyl-butyl-benzyl-methylamine

have shown that while the effects obtained with the different compounds vary to a certain degree, they are substantially the same.

All these numerous compounds exert a checking influence on the non-striated muscles and are capable of abolishing spasms of the non-striated muscles. In this respect these compounds have proved to be superior to the papaverine.

The new compounds according to this invention can be obtained by any of the methods

45 either, in order to obtain the typical papaverine effect, that both phenyl radicals present in the papaverine be substituted by alkoxy groups, but that the peculiar effect of the papaverine is obtained also if none or only one oxygen-containing group is present in the molecule.

The length of the carbon chain linking the phenyl radical to the nitrogen is of no avail as far as the effect is concerned.

50 55 Careful investigations into the properties of a

55

serving for producing tertiary amines. In the examples given below as illustrative of this invention some of these methods have been described by way of example.

5 In practising our invention we may for instance proceed as follows:

Example 1

Bis-phenethyl-ethylamine:

10 14 grams phenylethylchloride are heated 24 hours to 120° C. in a sealed tube together with 15 grams of a 33% alcoholic ethylamine solution and 5.6 grams soda. The solution is then acidulated by adding some hydrochloric acid of 5% and the alcohol and the non-basic fractions are driven off with steam. The residual watery solution is made strongly alkaline with caustic potash solution and extracted with ether. On fractionating the etheric solution the compound to be produced is obtained as a basic oil boiling under 8 mm. mercury column at 188 to 190° C. The hydrochloride forming white needles melts at 137° C.; it readily dissolves in water, but only with difficulty in ethylacetate.

25

Example 2

Bis-phenylethyl-allylamine:

30 14 grams phenylethylchloride and 6 grams allylamine are dissolved in 30 ccm. alcohol and heated 24 hours to 120° C. in a sealed tube. The product of reaction is treated further as described with reference to Example 1. The phenylethyl allylamine boiling under 7 mm. pressure at 109° C. is obtained, the yield being 35 85% of the calculated yield. In order to convert the compound into the tertiary base, 10 grams are heated 24 hours to 120° C. in a sealed tube together with an equal quantity of phenylethylchloride under addition of 30 ccm. alcohol 40 and 20 ccm. of a 20% caustic soda solution. The reaction mixture on being treated as described with reference to Example 1 results in 17 grams bis-phenylethyl-allylamine, an oil boiling under 4 mm. pressure at 182° C. The 45 hydrochloride forming white needles melting at 119-120° C., dissolves readily in water, but is insoluble in ether.

Example 3

Phenethyl-phenisopropyl-methylamine:

50 13 grams phenylethylamine and 14 grams benzylmethylketone are dissolved in 50 ccm. alcohol and hydrogenated in the presence of 3 grams of a 5% palladium-barium sulfate catalyst obtained by reducing a solution of palladious chloride with formaldehyde in the presence of barium sulfate and soda (see Houben-Weyl "Methoden der organischen Chemie", 3rd Ed. vol. 2, p. 500). When the absorption of hydrogen has come to an end, the mass is filtered, the alcohol removed by evaporation and the residual phenethyl-phenisopropylamine separated out under the form of the hydrochloride by adding some hydrochloric acid of 25%. The hydrochloride melts at 160° C. In order to convert the compound into the tertiary base 4 grams of the hydrochloride are heated 3 hours to 140° C. in a sealed tube together with 4 ccm. formaldehyde solution of 35%. After evaporation of the liquid from the reaction product the hydrochloride of phenethyl-phenisopropyl-methylamine remains over. On being recrystallized from ethylacetate to which has been added some ether, the compound is recovered in the form of white needles melting at 124° C. and dissolving readily

in water, but only with difficulty in ethylacetate.

Example 4

(Alpha, beta-diphenyl-ethyl-phenylethyl-propylamine:

5 5 grams phenylethylamine and 8 grams benzylphenylketone are heated 30 minutes to 120° C. The resultant product is dissolved in 50 ccm. alcohol and into the boiling solution are entered 5 grams sodium metal. When the development of hydrogen has come to an end, 100 ccm. water are added for dilution and the liquor is acidulated with hydrochloric acid of 25%, whereby the hydrochloride of (alpha, beta-diphenyl-ethyl-phenylethylamine, melting at 261° C. is separated out. To convert this compound to the tertiary base 5 grams of the hydrochloride are heated 12 hours to 120° C. in a sealed tube with 4 grams soda, 50 ccm. alcohol of 50% and 2.5 grams propylbromide. When the reaction has come to an end the alcohol is removed by evaporation, the watery residue rendered alkaline with caustic potash solution and extracted with ether. By adding to the extract an alcoholic solution of hydrochloric acid up to acid reaction, the hydrochloride of the new compound is separated out, 60% of the calculated quantity being recovered. The compound forms white needles melting at 263° C. and dissolving in water only with difficulty.

Example 5

O-methoxy-phenethyl-phenethyl-ethylamine:

35 3 grams o-methoxy-phenethylamine and 3 grams phenylacetaldehyde are dissolved in 30 ccm. alcohol and subjected to catalytic hydrogenation as described with reference to Example 3. The o-methoxy-phenethyl-phenethylamine thus obtained can be converted into a hydrochloride, 40 which is moderately soluble in water and melts at 142° C., the yield being 4 grams. 6 grams of the basic compound are heated 24 hours to 100° C. in a sealed tube with 4 grams ethylbromide, 2 grams soda and 40 ccm. alcohol of 50%. By 45 treating the resulting product further as described with reference to Example 1, the compound to be produced is obtained under the form of a basic oil, the hydrochloride of which forms white needles melting at 155° C. and dissolving only moderately in water, more readily in alcohol. The yield is 4.5 grams.

Example 6

Bis-(3,4-dimethoxy-phenethyl)-methylamine:

55 5 grams (3,4-dimethoxy-phenethyl)-amine are heated with 2 grams of the palladium-barium sulfate catalyst described with reference to Example 3 in the oil bath to about 225° C., while passing hydrogen gas through it, until no further 60 splitting off of ammonia can be noticed, which is the case after the lapse of about 1 hour. The residual product is dissolved in hydrochloric acid of 5%, the solution is filtered, caustic alkali in excess is added and the base extracted with ether 65 and precipitated from the etheric solution by adding alcoholic hydrochloric acid until an acid reaction is obtained. The hydrochloride crystallizes from alcohol under the form of white needles melting at 199° C. and dissolving in water only with difficulty. To convert it into the tertiary base, 4 grams of the hydrochloride thus obtained are heated in a sealed tube to 120° C. with 1 gram formaldehyde solution of 35% and 4 grams formic acid. By adding caustic alkali to 75

the solution until an alkaline reaction is obtained, the tertiary base is precipitated as an oil which quickly solidifies. The hydrochloride melts at 242° C., the yield is 70% of the calculated yield. It forms white needles which dissolve rather readily in alcohol, but only with great difficulty in ethylacetate.

Example 7

- 10 Beta-methoxy-beta-phenethyl-phenethylmethylamine:
 3.2 grams beta-methoxy-beta-phenylethylamine and 3 grams phenylacetaldehyde are dissolved in 30 ccm. alcohol and subjected to catalytic hydrogenation as described with reference to Example 3. On distillation of the resulting solution there is obtained the beta-methoxy-phenethyl-beta-phenethylamine under the form of a liquid boiling under 15 mm. pressure at 213-215° C. On 4 grams of the base being treated with formaldehyde and formic acid, as described with reference to Example 6, the hydrochloride of the tertiary base is obtained, the yield being 70%. It forms white needles dissolving in alcohol and liquefying at 100° C.

Example 8

- Gamma-phenyl-propylbenzyl-methylamine:
 1/20 mol. benzyl-methylamine are heated 15 hours in a sealed tube to 120° C. with 1/20 mol. phenylpropylchloride, 1/20 mol. soda and 50 ccm. alcohol of 50%. After evaporation of the alcohol the residue is rendered strongly alkaline and extracted with ether, to the etheric solution is added alcoholic hydrochloric acid of 10%, until the solution shows an acid reaction and the hydrochloride of the new compound is thus precipitated under the form of an oil, which gradually crystallizes, forming white needles melting at 146° C. and dissolving in water, but being insoluble in ether. The yield is 75% of the calculated yield.

Example 9

- 45 Bis-(gamma-phenyl-propyl)-ethylamine:
 1/20 mol. bis-(gamma-phenylpropyl) amine, 1/20 mol. ethylbromide and 1/20 mol. soda are heated together with 50 ccm. alcohol of 50% to 120° C. in a sealed tube. The resulting product is 50 treated further as described with reference to Example 8. One thus obtains the hydrochloride of the new compound which does not crystallize and is soluble in water, but dissolves only with difficulty in ethylacetate. The yield is 70%. Its perchlorate melts at 70° C.

Example 10

- Delta-phenyl-butyl-benzyl-methylamine:
 1/20 mol. benzyl-methylamine, 1/20 mol. delta-phenyl-butyl-chloride, 1/20 mol. soda and 50 ccm. alcohol of 50% are treated as described with reference to Example 9. One thus obtains the hydrochloride of the tertiary base forming white needles melting at 113° C., and being soluble in water, but insoluble in benzene. The yield is 65%.

Various changes may be made in the details disclosed in the foregoing specification without departing from the invention or sacrificing the advantages thereof.

The compounds within the scope of our invention can be defined by the generic formula

wherein R_1 and R_2 represent phenyl or alkoxy-substituted phenyl groups, A_1 and A_2 represent alkylene chains or phenyl- or alkyl-substituted alkylene-chains of the lower aliphatic series, and R_3 represents an unsubstituted aliphil group of the lower aliphatic series. By the term "aliphil group" we mean an alkyl group or an unsaturated hydrocarbon group, such as allyl for example.

One of the processes of our invention comprises condensing a primary amine of the class consisting of $R_1-A_1-NH_2$, $R_2-A_2-NH_2$ and R_3-NH_2 with a compound selected from a secnd class consisting of R_1-A_1-X , R_2-A_2-X and R_3-X , under conditions of reaction producing liberation of HX and with formation of a secondary amine of the class consisting of

$R_1-A_1-NH-R_3$ and $R_2-A_2-NH-R_3$, and condensing the resulting secondary amine with a compound selected from a class consisting of R_3-X , R_2-A_2-X and R_1-A_1-X , respectively, under conditions of reaction producing liberation of HX and with formation of a tertiary amine of the aforesaid generic formula; X being a group, such as halogen, aldehyde, ketone, sulfate or sulfo-acid, capable of uniting with an available hydrogen atom of said amines under said conditions of reaction with liberation of HX .

We claim:—

1. Bis-(gamma-phenyl-propyl)-ethylamine, the hydrochloride of which does not crystallize and is soluble in water, the perchlorate melting at 69 to 70° C. and being difficultly soluble in water, but readily soluble in acetic acid ester.

2. Bis-phenylethyl-ethylamine, a basic oil boiling under 8 mm. pressure at 188 to 190° C., the hydro-chloride forming white needles melting at 137° C. and readily dissolving in water, but only with difficulty in ethylacetate.

3. Bis-(3,4-dimethoxy-phenethyl)-methylamine, an oily product, which solidifies quickly, its hydrochloride forming white needles melting at 242° C. and dissolving rather readily in alcohol, but only with great difficulty in ethylacetate.

4. The process of preparing bis-phenethyl-ethylamine which comprises heating a phenyl-ethyl halide with ethylamine.

5. The process of preparing bis-(3,4-dimethoxyphenethyl)-methylamine which comprises subjecting 3,4-dimethoxyphenethyl-amine to a catalytic hydrogenation and methylating the resulting product.

6. The process of preparing bis-(gamma-phenyl-propyl)-ethylamine which comprises heating bis-phenyl-propylamine with an ethyl halide.

7. Tertiary amines of the aliphatic-aromatic series having the generic formula

wherein R_1 and R_2 represent phenyl or alkoxy-substituted phenyl groups, A_1 and A_2 represent alkylene chains or phenyl- or alkyl-substituted alkylene-chains of the lower aliphatic series, and R_3 represents an unsubstituted aliphil group of the lower aliphatic series.

8. In the manufacture of tertiary amines of the aliphatic-aromatic series having the generic formula

wherein R_1 and R_2 represent phenyl or alkoxy-substituted phenyl groups, A_1 and A_2 represent alkylene chains or phenyl- or alkyl-substituted alkylene chains of the lower aliphatic series and 5 R_3 represents an unsubstituted aliphyl group of the lower aliphatic series; the process which comprises condensing a primary amine of the class consisting of

10 $R_1-A_1-NH_2$, $R_2-A_2-NH_2$ and R_3-NH_2 , with a compound selected from a second class consisting of

R_1-A_1-X , R_2-A_2-X and R_3-X ,

15 under conditions of reaction producing liberation of HX and with formation of a secondary amine of the class consisting of

$R_1-A_1-NH-R_2-A_2$, $R_1-A_1-NH-R_3$ and
20 $R_2-A_2-NH-R_3$

and condensing the resulting secondary amine with a compound selected from a class consisting of

25 R_3-X , R_2-A_2-X and R_1-A_1-X ,

respectively, under conditions of reaction producing liberation of HX and with formation of a tertiary amine of the aforesaid generic formula; X being a group capable of uniting with an available hydrogen atom of said amines under said 30 conditions of reaction with liberation of HX .

9. In the process of manufacturing tertiary amines of the aliphatic-aromatic series having the generic formula

5

wherein R_1 and R_2 represent phenyl or alkoxy-substituted phenyl groups, A_1 and A_2 represent alkylene chains or phenyl- or alkyl-substituted alkylene chains of the lower aliphatic series and R_3 represents an unsubstituted aliphyl group of the lower aliphatic series; the step which consists of condensing a secondary amine of the class consisting of

10 $R_1-A_1-NH-A_2-R_2$, $R_1-A_1-NH-R_3$ and
 $R_2-A_2-NH-R_3$

with a compound selected from the class consisting of

15 R_3-X , R_2-A_2-X and R_1-A_1-X ,

respectively, under conditions of reaction producing liberation of HX and with formation of a tertiary amine of the aforesaid generic formula; X being a group capable of uniting with the hydrogen atom of the amine group of said secondary amines under said conditions of reaction with liberation of HX .
